Primary Examiner — Angela J Lee*(74) Attorney, Agent, or Firm* — Michael Best & Friedrich LLP(57) **CLAIM**

We claim the ornamental design for a headlight nacelle, as shown and described.

DESCRIPTION

FIG. 1 is a top front right perspective view of a headlight nacelle;

FIG. 2 is a bottom front left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom view thereof; and,

FIG. 9 is a left side elevation view of the headlight nacelle on a motorcycle.

The broken lines in FIGS. 1-4, 7, and 8 define the bounds of the claimed design and form no part thereof. The broken lines in FIG. 9 are for the purpose of illustrating the environment of the headlight nacelle and form no part of the claimed design.
